[57] CLAIM

The ornamental design for a traffic channelization
drum or the like, as shown and described.

DESCRIPTION

FIG. 1 is a front perspective view of a traffic channelization
drum or the like showing our new design;
FIG. 2 is a left-hand end view thereof, the right-hand
end view being a mirror image;

FIG. 3 is a rear end view thereof;
FIG. 4 is a front end view thereof, and
FIG. 5 is a bottom plan view thereof.

The drum is stippled to indicate contrast. The warning
light is shown in broken lines in FIGS. 1, 2, 3 and 4 for
illustrative purposes only.
